UNITED STATES PATENT OFFICE.

VERNA O'NEAL WATKINS, OF ATLANTA, GEORGIA.

EDUCATIONAL TABLE.

Application filed January 4, 1922. Serial No. 526,913.

To all whom it may concern:

Be it known that I, Verna O'Neal Watkins, a citizen of the United States, residing at Atlanta, in the county of Fulton and State of Georgia, have invented certain new and useful Improvements in Educational Tables; and I do hereby declare the following to be a full, clear, and exact description of the invention, such as will enable others skilled in the art to which it appertains to make and use the same.

This invention relates to improvements in educational apparatus of that type disclosed in Letters Patent 1,392,726, granted to me October 4th, 1921, and more particularly to improvements in that type disclosed in my application filed May 20th, 1920, Serial Number 382,839, and allowed May 20, 1921.

The primary object of the present invention is the provision of an educational apparatus wherein the body, which like the body of the apparatus disclosed in said allowed application is provided at one side with a drawing board and at its other side with a perforated board, may be readily and quickly reversed so as to present either of said boards in position for use, without necessitating the detachment or removal of the body from its support.

A further object of the invention is the provision of an educational apparatus of the kind stated wherein the reversible body may be supported at any desired angle with respect to the horizontal.

A still further object of the invention is the provision of an educational apparatus of the kind set forth wherein the body is provided with conveniently located receptacles for chalk, pegs, pastes and like articles used in connection with the apparatus.

With the above and other objects in view, the invention consists in the construction, combination and arrangement of parts hereinafter fully described and claimed, and illustrated in the accompanying drawings, wherein:

Figure 1 is a view in front elevation of an educational apparatus constructed in accordance with the present invention, the body being shown in position with the blackboard uppermost or in position for use.

Figure 2 is a view similar to Figure 1 illustrating the perforated board uppermost or in position for use.

Figure 3 is a detail sectional view illus-

trating the manner in which the body is secured to its support,

Figure 4 is a perspective view of fragmentary parts of the body and its support,

Figure 5 is a view in end elevation of the apparatus, the lower portion of the support being broken away,

Figure 6 is a view in end elevation of the body of the apparatus,

Figure 7 is a detail perspective view of one of the clamping plates for the legs of the support,

Figure 8 is a detail perspective view of another of the clamping plates for the legs of the support,

Figure 9 is a detail perspective view of the plates shown in Figure 8, viewing the opposite side of the plate, and

Figure 10 is a detail perspective view of the easel.

Like reference characters designate like or similar parts throughout the views.

In reducing the invention to practice, a reversible body A is provided. The body A has a perforated peg receiving board B at one side. At one end of the board B, a receptacle 10 is provided within the body to conveniently contain the pegs 11 which are insertible into the perforations of the board B according to the disclosures in said patent and allowed application. The opposite side of the body A is provided with a blackboard surface or drawing board C and a receptacle at one end thereof for pencils, crayons and the like. Over the receptacles, closures or covers 12 are provided, being hinged to the body as at 13. When in closed position the outer surfaces of the closures 12 are flush with the outer surfaces of the body A. The closure 12 may be fastened against accidental opening by means of hasps 14 co-operating with staples or fastenings 15 on one of the lateral sides of the body A. These receptacles form a very efficient and convenient means to retain the pegs, pencils, crayons, etc., especially in view of the fact that the user may remove them from the receptacles and use them in connection with the board B or board C without a change in his position.

At each end of the body A two legs are provided as at 16. Each pair of legs 16 are in inclined or converging relation, and are connected at their upper ends. Plates 17 and 18 are disposed on opposite sides of the

legs, being secured thereto, as by means of bolts or the equivalent 19. These plates 17 and 18 are provided on their inner surfaces with inner V-shaped flanges 20 and outer flanges 21. Flanges 20 are disposed intermediate the legs 16 and the flanges 21 overlap the outer sides of said legs. In other words, the flanges 20 and 21 provide wide grooves into which the legs 16 fit. Such flanges 20 and 21 efficiently reinforce the legs 16 and connect them at their upper ends.

On plate 17, a raised serrated rosette 22 is provided. Fastened to each end of the body A, is a disc or plate 23 secured as by means of bolts or screws 24 and which has raised portions 25 forming a serrated rosette similar to the rosette 22. Rosettes 22 and 23 are adapted for interengagement and the bolt 26 extends through the plate 23. The bolts 26 pass through suitable openings in the end boards of body A, the plates 17 and 18 and legs 16, and beyond the plates 18 the bolts receive fastening nuts 27, preferably in winged form to facilitate manipulation by means of the fingers. Such disposition enables the removal of the bolts so as to avoid their projecting from the casting when the device is in portable form. Detachments of bolts 26 enables legs 16 to be removed and inserted for compact packing or portage into body A, as covered in my said Patent 1,392,726.

When the nut 27 is tightened, it will be realized that the rosettes 22 and 23 will be in intimate interfitting contact and will thus hold the top against turning from the bolt or pivot 26 relative to the legs 16. When it is desired to reverse the body B or vary the angle thereof, nut 27 is loosened and the body A then appropriately adjusted, after which the nut 27 is again tightened so that the rosettes 22 and 23 will interengage and secure the body in the adjusted position.

An easel D may support sheets, books or other instruction mediums E as in my said patent. This easel is of simplified construction to that of the patent, preferably being made of a single strand of wire including clamping and retaining coils 28 and legs

29 to detachably engage sockets 30 on the body A. The easel may be removed when desired and packed or carried within the body A as disclosed in my said patent. 65

This construction enables reversal to present either board B or C uppermost simply by swivel movement on bolts 26 which is permissible when nuts 27 are loose. Also regardless of which board is uppermost, the 60 easel C may be positioned in the appropriate brackets 30 so as to be located in the rear or same side of the table and in the same position with respect to the student or user. This is greatly advantageous over 65 the construction of the said allowed application where the top has to be detached or removed in order to reverse it.

It is to be understood that changes in the principles may be resorted to inasmuch as 70 I have shown merely one practical embodiment since variations are possible within the spirit and scope.

Having thus described the invention, what I claim is:— 75

1. An educational apparatus having a body, legs, disposed at an angle to each other, inner and outer plates, bolts passing through said plates and legs, said plates having substantially central V-shaped 80 flanges disposed intermediate and abutting the legs, said plates having outer flanges overlapping the legs, a rosette on one of said plates, a rosette on said body, and a fastening bolt extending from said body and passing through said rosettes. 85

2. An educational apparatus comprising a body having a drawing board and a work board, legs to which said body is pivoted for reversal to selectively present said boards 90 in utilize position, brackets at each side of the body in planes intermediate said boards, and an easel detachably engageable with said brackets whereby it may be secured in the same position with respect to the same student in either position of the body. 95

In testimony whereof I affix my signature in presence of two witnesses.

VERNA O'NEAL WATKINS.
